UNITED STATES PATENT OFFICE.

EDMUND S. DICKEY, OF BALTIMORE COUNTY, MARYLAND, ASSIGNOR TO AMERICAN METER COMPANY, INC., OF NEW YORK, N. Y., A CORPORATION OF DELAWARE.

GUIDE FOR DRY-TYPE-GAS-METER VALVES.

1,306,220.

Specification of Letters Patent. Patented June 10, 1919.

Application filed June 28, 1918. Serial No. 242,426.

To all whom it may concern:

Be it known that I, EDMUND S. DICKEY, a citizen of the United States, residing at Baltimore county, and State of Maryland, have 5 invented certain new and useful Improvements in Guides for Dry-Type-Gas-Meter Valves, of which the following is a specification.

This invention relates to improvements in 10 guides for valves of dry-type gas meters.

One object of the invention is to provide a guide that will insure accurate reciprocatory sliding movement of the valve cover on its seat and to provide a construction, due to 15 which the valve cover will be guided, with the least possible lateral or side motion and, at the same time, with the least amount of friction in the operation or movement of the guiding parts. Also, to provide a construction, due to which the valve cover can be 20 readily lifted from its seat without the necessity of any considerable sliding movement of the cover beyond that incident to its normal sliding movement in operation.

It is important in constructing dry-type 25 meters, that space within the casing be economized to the fullest extent so that the unit itself may be reduced in size as much as possible in proportion to the capacity of the 30 meter. With the guide about to be described, the valve cover may be put in place by virtually dropping it upon its seat and without the necessity as in other types of 35 guides, for moving the valve cover to a position where the guides carried by the cover are being brought in position to clear the guide eyes or brackets at the ends of the valve seat, thus economizing space and adding to the convenience of assembling the 40 parts in the first instance, and, due to the peculiar construction and serrated edges of the guide about to be described, obtaining ease in operation for repairs and cleaning on same.

In the drawings illustrating the invention:

Figure 1 is a top plan view of the valve of large capacity, constructed in accordance with my invention, showing the valve cover 50 in central position, or in the position in which the ports in the valve seats are closed.

Fig. 2 is a similar view of one side of the valve, with the cover in one extreme position, or the position in which some of the

ports in the valve seat are open, there being 55 also shown in dotted lines in this view, the position of the valve cover in which it can be lifted from its seat.

Fig. 3 is a cross section of the valve, taken 60 on line *a-a* of Fig. 1.

Referring to the drawing, the numeral 1 designates a portion of a valve table, such as is commonly employed in meters of this type. The numeral 2 designates the valve seat, which is provided with inlet and outlet 65 ports, and since the construction of the valve seat is unimportant in this application, it need not be particularly described with reference to the diaphragm, casing and outlet ports. The valve seat is like that shown and 70 described in my application Serial Number 223,577, filed March 27, 1918, and is provided with side bars 3 and front and rear bars 4, and central bar 5.

The numeral 6 designates the valve cover, 75 with which, in carrying out my invention, I provide two ears or brackets 7, at each side of the cover, or four in all, the brackets being of angular formation as shown best in Fig. 3, and each bracket is provided with a ledge 8 whose outer faces are preferably serrated as indicated at 9, to reduce friction and make the valve cover in its coöperation with the guide bars, self-cleaning. These brackets are held in position and guided in their 80 movement by two side guide bars 10, so that the side thrust or lateral movement of the valve cover, due to the side pull or side thrust of the valve arm, will be practically 85 eliminated, there being provided only sufficient play or lateral motion between the angular brackets and guide bars to prevent friction or binding in the movement of the brackets against the guides.

The numeral 10 designates two guide bars 95 which are firmly secured to the valve table, parallel with the sides of the valve seat and each bar is provided with a laterally extending flange 11, which overlies the ledges of the brackets, carried by the valve cover. 100 The flange is recessed centrally as indicated at 12, the recess being slightly wider than the brackets 7, so that the brackets may pass through the recess in placing the valve cover upon its seat, or removing the same.

It will be noted that the positions of the brackets on the valve cover are such that, under the side thrust or lateral movement

of the cover and owing to the serrated edge of the brackets, a very small bearing surface is provided thus decreasing friction but allowing and providing for any possible 5 wear at contact points in the movement of the brackets against the guide bars.

It will be noted that the positions of the brackets on the valve cover are such as to effectually prevent any tilting, as well as 10 to prevent any lateral movement of the valve cover upon its seat.

The numeral 13 designates a valve arm which is shown broken away, but it will be understood that this arm extends to and 15 is connected with the operating shaft of the meter, through which the necessary reciprocatory movement is imparted to the valve.

It will be noted that the side bars are so proportioned with respect to the extent 20 of movement of the valve cover, that in normal operation of the valve, the brackets will never be free of, or from under, the overlying flange of the bars, but when the valve arm is disconnected and it is desired to re- 25 move the valve cover, it is only necessary to give to the cover, a short movement in either direction, slightly in excess of that equal to its normal movement, when a bracket on each side of the cover will clear 30 the end of the side guide bar 10, and the other two will register with the recesses 12 in the side guide bars, when the cover can be lifted off or seated, as the exigencies of the case may require.

35 Having thus described my invention, what I claim is:

1. A valve guide of the character described, comprising a valve cover provided 40 with extensions on each side thereof, a suitably supported guide bar at each side of the cover and having a portion overlying the extensions on the cover, the overlying portions of the guide bars being provided with open sided recesses for the passage of

the extensions of the cover, to facilitate the 45 removal of said cover.

2. A valve guide of the character described, comprising a valve cover having two brackets on each side thereof, and adjacent the ends of the cover, and a suitably supported guide bar at each side of the valve cover and provided with a flange overlying the brackets, the overlying portion of each bar being provided with an open topped recess for the passage of a bracket on each 55 side of the cover, to facilitate the removal of the cover from its seat.

3. A valve guide of the character described, comprising a valve cover, provided at each side and near the ends thereof with 60 two downwardly extending brackets, each bracket provided with a laterally extending ledge, a guide bar adjacent each side of the cover and having a portion overlying the ledges of the brackets, the overlying portion 65 of each bar being provided with an open sided recess for the passage of the brackets in removing from, or seating the valve upon its seat.

4. A valve guide of the character described, comprising a valve cover having two brackets on each side thereof and adjacent the ends of the cover, each bracket being provided with a serrated edge, and a suitably supported guide bar at each side 75 of the valve cover, and provided with a flange overlying the brackets, the overlying portion of each bar being provided with an open topped recess, for the passage of a bracket on each side of the cover, to facilitate the removal of the cover from its seat.

In testimony whereof I affix my signature in presence of two witnesses.

EDMUND S. DICKLEY.
